The ornamental design for an inner housing for an optical fiber adapter, as shown and described.

DESCRIPTION

FIG. 1 is a top perspective view of an inner housing for optical fiber adapter showing the new design; FIG. 2 is a bottom perspective view thereof;

FIG. 3 is a top plan view thereof;

FIG. 4 is a bottom plan view thereof;

FIG. 5 is a front view thereof, the rear view being a mirror image thereof;

FIG. 6 is a left side view thereof, the right side view being a mirror image thereof; and,

FIG. 7 is a perspective view thereof, shown in an environment of use.

The broken line portion of the figure drawings is included to show environment that forms no part of the claimed design.
